V. J. WATERS

VALVED PISTON

Filed Oct. 1, 1925

UNITED STATES PATENT OFFICE.

VICTOR J. WATERS, OF SHIDLER, OKLAHOMA, ASSIGNOR OF ONE-THIRD TO HENRY S. MERCER, OF SHIDLER, OKLAHOMA.

VALVED PISTON.

Application filed October 1, 1925. Serial No. 59,956.

This invention relates to improvements in valved pistons for fluid pumps, and specifically to a piston construction for use in oil wells. The invention is known in the practical art as a "travelling valve".

In raising or pumping of liquids including oil from deep wells, it is usually found that sand and other gritty sediment is raised along with the fluid, and difficulty has been experienced in protecting the pump piston from rapid wear due to the cutting action of the sand and grit which lodges between the piston and working barrel and in a short time makes it necessary to renew the piston packing elements, or to install an entirely new piston. In practice, various expedients have been tried to properly protect the piston particularly against the cutting action of sand; and among these may be mentioned the use of a brush-like arrangement carried by the piston which is intended to act as a rough mechanical filter to catch the sand and grit. Also expansive metallic piston rings have been used, but neither of these devices, to the best of my knowledge, has been effective to adequately protect the piston.

The object of my invention is to provide effective protection for the pump piston against the cutting action of sand and grit, to thereby prolong the useful life of the device and increase its efficiency.

The details of the improved construction will be described in connection with the accompanying drawing which forms a part of this specification, and in which

Fig. 1 is a side elevation of my improved "travelling valve" showing a preferred relative arrangement of the elements;

Fig. 2 is a part sectional view showing the details of the invention in the arrangement of Fig. 1;

Fig. 3 is a side elevation of another and optional relative arrangement of elements in which the protection against entrance of sand is located beneath the piston packing.

Referring first to Fig. 1, the piston structure comprises a series of superposed cup-like elements 1, which are supported and aligned on a central tube 3, by the flanged sleeves 2. The cups 1, are preferably of leather, but other fibrous material or compositions may be used, and the number of cups employed may be varied depending on certain practical conditions such as depth of

well, etc. At the lower end of the piston, 55 the bottom cup rests on a washer which in turn is supported on locked nuts 4, threaded upon the outside of tube 3.

The upper sleeve 2 abuts a hollow cylindrical element 5, which is fixed to the tube 60 3, by a pin or rivet 6. In assembling this part of the device the cups 1, and sleeves 2 to the desired number, are placed upon the tube 3, and are pressed together and against the fixed stop 5, by adjusting the nuts 4. 65 The series of cups constitute the piston and its packing and are designed to fit closely within the working barrel which is not shown. It is to protect these cups from sand and grit which constitutes the principal object of my invention, and this is accomplished by properly associating with the other elements of the piston construction a particular type of expansion packing which will now be described.

Surrounding the central tube 3, and extending a substantial distance longitudinally thereof is a flexible fibrous packing section 7. This packing may be made tubular, or it may be formed by building up convolutions of a rope-like fibrous packing which is covered with an outer coating or protecting covering which serves to maintain the structure in tubular form. The packing is also preferably impregnated with a graphitic composition which improves its wearing properties by reducing friction and rendering the packing impervious to watery solutions.

The packing section 7, is supported at one 90 end, the lower end in Figs. 1 and 2, in a counter-bored recess in the upper end of the fitting 5; and at its opposite end is retained within a similar cup-like recess in the lower end of the movable sleeve 8. The latter 95 element is supported to slide freely on the tube 3, and is pressed against the packing 7, by the force of a compression spring 9. It will be seen, therefore, that the packing 7, is held between a fixed and sliding abutment and is at all times subjected to a compression force which tends to reduce its length and to increase its effective diameter. Since its diameter is limited by the working barrel in which it slides, the result of the compressive force is to expand the packing into close fitting contact with the working barrel over a relatively long section of the barrel,

and in this way form a very effective closure and seal against passage of sand or grit.

The coil spring 9 is retained in position at its upper end by a fitting 10, which is fixed to the tube 3. This fitting includes a seat at its upper end for a ball valve 12 retained within the cage 11; and an operating rod for the piston (not shown) may be secured to a threaded extension at the upper end of the cage.

In operation as the piston is raised within the working barrel, oil or other fluid will rise therein, and as the piston moves downwardly the fluid will pass the valve 12, and 15 flood the tubing as far down as the packing 7, where sand or gritty substances entrained with the oil will be stopped by the packing 7, and thereby prevented from reaching the cups 1.

It may also be found desirable to arrange a packing element 7, below the cups 2, and such an arrangement is illustrated in Fig. 3, with the movable abutment 8, beneath, and the fixed abutment 5, above the packing. 25 The remaining details of this modified construction are the same as already described in connection with Fig. 1. It is obvious also that packing elements of this construction can be arranged both above and below 30 the cups on the same piston, and other changes within the range of mechanical equivalents may be made without departing from the scope or spirit of my invention which is claimed as follows:

I claim:

1. In a valved piston comprising a central tube supporting intermediate its ends a series of cup-like piston elements, and a valve at one end only of the tube, a sleeve of fibrous packing surrounding the tube adjacent the piston elements, the said sleeve being held against a fixed abutment at one end, and a sliding abutment at the opposite end which is guided by the central tube and yielding means effective at all times to move the sliding abutment toward the fixed abutment to compress the packing sleeve whereby its effective diameter is increased substantially throughout its length. 40

2. In a valved piston comprising a central tube supporting intermediate its ends a series of cup-like piston elements, and a valve at one end only of the tube, a sleeve of fibrous packing surrounding the tube adjacent the piston elements, a fixed abutment for the sleeve at one end and a sliding abutment for the sleeve at the opposite end, both said abutments having cup-like depressions in their ends to receive and hold the ends of the packing sleeve, a coiled compression spring 50 surrounding the tube and supported thereon to exert its force against the sliding abutment to compress the packing sleeve and thereby increase its effective diameter. 55

In testimony whereof I hereunto affix my 60 signature.

VICTOR J. WATERS.
